UNITED STATES PATENT OFFICE.

CLARENCE G. GARRIGUS AND HERBERT W. SPELLMAN, OF NEW BRITAIN, CONNECTICUT,
ASSIGNORS TO LANDERS, FRARY AND CLARK, OF NEW BRITAIN, CONNECTICUT, A COR-
PORATION OF CONNECTICUT.

GRINDING-MACHINE.

No. 893,158.

Specification of Letters Patent.

Patented July 14, 1908.

Application filed October 3, 1907. Serial No. 395,727.

To all whom it may concern:

Be it known that we, CLARENCE G. GARRIGUS and HERBERT W. SPELLMAN, both citizens of the United States, residing at New 5 Britain, in the county of Hartford and State of Connecticut, have invented certain new and useful Improvements in Grinding-Machines, of which the following is a specification.

10 Our invention relates to improvements in grinding machines and the objects of our improvements are simplicity and economy in construction, and convenience and efficiency in use. This is particularly the case with 15 reference to the control of the carriage and the longitudinal adjustment of the grinding spindle.

In the accompanying drawing: Figure 1 is a plan view of our machine. Fig. 2 is an 20 elevation of the same, showing an end view of the machine, (the bottom end of Fig. 1) with a side-view of the carriage. Fig. 3 is a broken out sectional elevation of the same on the line *x x* of Fig. 1. Fig. 4 is an enlarged 25 broken out sectional elevation of the same on the line *y y* of Fig. 1. Fig. 5 is an end view of the carriage and parts immediately connected therewith. Fig. 6 is an enlarged horizontal section of the three-way cock on the line *z z* 30 of Fig. 5, which cock belongs to the hydraulic engine that operates the carriage.

The machine as shown is especially adapted for grinding table knives.

A designates the frame of the machine, 35 which frame may be supported on any suitable legs 7. Mounted upon the frame in suitable bearings is the spindle or shaft 8 of the hollow grinding wheel 9. In front of this grinding wheel there is a swinging carriage 40 bed 10 that is pivoted to a bracket 11 of the frame on the pin 12, Fig. 4. Upon this carriage frame is a reciprocating carriage 13 and a hydraulic engine 14, for operating the same for carrying a knife when attached to the 45 said carriage across the face of the rim of the hollow grinding wheel 9.

The machine as thus far specifically described is older than our invention which is in the nature of an improvement on the machine so described. We employ a new construction for adjusting the spindle of the 50 grinding wheel longitudinally and a new mechanism for controlling the engine whereby it is mainly controlled by the direct action 55 of its piston rod.

The tail end of the spindle 8, may be supported in any ordinary form of box or bearing 15. The opposite end is supported in a tubular sleeve 16 that is slidably held to the frame by a cap 17 and prevented from rotating therein by an ordinary spline 18, Fig. 3. I prefer to taper the spindle and sleeve at the outer end, or end nearest the grinding wheel, as shown in Fig. 3. The spindle is provided with a threaded portion 19, Fig. 3, near the 60 loose pulley 20, and its companion fast pulley 21. Upon the threaded portion of the spindle is a clamp nut 22, of ordinary construction and having one or more ordinary clamp screws, not shown. By screwing up 65 this nut the tapering portions of the spindle may be tightened within the tubular sleeve 16 and held against longitudinal movement therein. That end of the tubular sleeve which is not covered by the cap 17 is externally threaded as at 23 and upon this threaded portion is a nut 24 provided with a rim in the form of a hand wheel 25. This nut abuts by one end against the end of the cap 17 and a part of the frame in the plane of the said 70 end of the cap. It is provided with a shoulder 26 which is opposed to this abutting end of the nut and clips 27, Fig. 1, are secured to the frame for engaging this shoulder to hold the nut against longitudinal movement while 75 at the same time the nut is free to rotate. By rotating the nut the grinding spindle and attached parts may be moved bodily endwise 80 so as to adjust the grinding wheel toward or from the carriage as may be required. 85

The carriage 13 is provided with a bed or seat 28 to which any desired holder may be secured in any ordinary manner. It is shown as adapted for receiving an ordinary form of knife holder. Projecting at right 90 angles to the said bed 28 is a short arm 29 and a longer arm 30 which latter may be called the cross arm of the carriage. The carriage ways are in part formed by a bar 31 that is rigidly secured within the arms 29 and 100 30 and which bar slides through proper bearings in the boxes 32 and 33 that project upwardly from the carriage bed. The outer end of the cross arm 30 of the carriage is slotted and slides upon a bar 34 that is rigidly 105 mounted on the carriage bed in a position parallel to the bar 31 upon which the carriage ways are formed.

The hydraulic engine or cylinder 14 is provided with a piston 35 and piston rod 36, 110

the said piston rod extending transversely through a hole in the cross arm 30 and for convenience we prefer to form a longitudinal groove 37 in the upper side of the piston rod, 5 whereby a bent rod resting in the said groove and having a projecting tripping lug 38 at one end, may be adjustably held on the piston rod by means of a collar 39 and set screw 40, as shown in Fig. 4. This lug is for tripping the latch 50 that is pivoted to the open end of the cylinder 14. We also employ adjustable collars 41 and 42 with set screws 43 secured to the said piston rod on opposite sides of the cross arm 30. To the collar 41 10 we secure the chain 44 that runs over a pulley 45 to a weight 46 for moving the carriage in one direction. The other collar 42 has secured to its under side a friction roller 65 for acting upon the end of the angle lever 47. 15 This angle lever is pivoted to the under side of the cross arm 30 of the carriage as at 48 and carries a friction roller 74 in the outer end of its shorter arm, which roller acts upon a fixed bar 49 that is mounted on the frame 20 25 A. The cylinder head 51 is provided with an ordinary three-way cock 52 having a tapering plug 53 provided with a transverse passage 54 opening on opposite sides and a passage 55 at a right angle thereto, see Fig. 6. 30 The socket or body of the cock has three ports, of which the port 56 is the inlet, the port 57 is the cylinder inlet and outlet, and the port 58 is the outlet of the cock. The cock is connected with the cylinder head 51 35 by the nib 61, the supply pipe 59 is connected with the cock by the supply nib 60, a suitable discharge pipe 62 is connected with the nib 63. This discharge pipe is provided with a regulating cock 64 which governs the discharge of the water by opening or closing the 40 said cock more or less to increase or diminish the amount of water discharged therefrom. The plug 53 of the cock 52 that controls the flow of the liquid into and out of the cylinder 45 is provided with an operating handle 66. On the top of the cylinder is a sliding bolt 67 having a beveled head for being engaged by the latch 50. This latch is forced upwardly by a small spiral spring 68, Fig. 4, placed 50 under its horizontal arm. Upon the sliding bolt 67 is an adjustable collar 69 that acts against a lug or upward projection of the cylinder head 51 to limit the movement of the sliding bolt towards the cock 52. An 55 adjustable collar 70 is rigidly clamped on the body of the sliding bolt and between that collar and the lug 71 in which the said bolt slides there is a spiral spring 72, that acts with a constant tendency to force the said bolt towards the cock 52. The handle 66 of the cock 52 is connected with the collar 70 by means of a rod 73.

When the handle 66 of the cock 52 stands in the position shown in the drawing the passages in the plug put the cylinder in commu-

nication with the discharge pipe so that the water runs out through the port 57, passage 55, one end of passage 54 and the port 58, to the discharge pipe 62 and the weight 46 will draw the piston and carriage back into the position shown. Pushing the handle towards the cylinder will force the sliding bolt towards the latch 50 until the beveled head depresses the latch and is engaged thereby as the hook of the latch passes the shoulder of the said head, thereby locking the sliding bolt in place against the force of its spring and also holding the cock in the open position which it was given by moving the handle. The movement thus given to the plug of the cock closes the outlet port 58 and opens the inlet port 56. The port 57 between the cock and the cylinder is never closed. The water from the supply pipe now rushes into the cylinder through the ports 56 and 57, and drives the piston and piston rod and connected parts outwardly, while the weight 46 is raised. As soon as the collar 41 engages the cross arm 30 of the carriage, the carriage is moved with the piston rod. As the piston and carriage reach the end of their stroke the tripping lug 38 (see Fig. 4) on the piston rod engages the depending arm of the latch 50 so as to release the said latch from its hold on the beveled head of the sliding bolt 67 upon which the release spring 72 acts to force the said bolt and handle of the cock 52 back into the position shown so that the port 56 is closed and the ports 57 and 58 opened to let the water out of the cylinder for moving the carriage backwardly under the influence of the weight 46. About the time that the piston rod reaches the outer end of its stroke the fixed friction spring 75 engages a shoe on the collar 76 of the bar 31 so as to tend to hold the carriage against a return movement. During the outward movement of the carriage the spring 77 that is secured by one end to the frame and by its other end to the swinging carriage has held the carriage slightly away from the grinding wheel so that the said wheel does not act on the work during the forward stroke of the carriage. When the carriage bed 10 is swung on its pivot 12 away from the grinding wheel the longer arm of the lever 47 swings forwardly into engagement with the roller 65 underneath the collar 42 on the piston rod. When the piston rod starts on its backward movement the friction devices, that is the spring 75 fixed on the carriage bed and the collar and shoe 76 fixed on the carriage, tend to hold the carriage against moving with the said rod so that the roller 65 may act on the angle lever 47 to shift it and press the roller 74 against the fixed bar 49 for swinging the carriage bed 10 towards the grinding wheel to bring the said wheel into action on the return stroke of the carriage. After the lever 47 has been moved sufficiently to thus 130

shift it, the collar 42 engages the cross arm 30 of the carriage and pulls the carriage back while the angle lever 47 holds the knife holder of the carriage to its work on the face 5 of the grinding wheel during its return stroke. By throttling the discharge by means of the cock 64, the return stroke of the carriage can be made as low as may be desired, while opening the said cock more or less will increase the 10 return speed of the carriage. The spring 77 acts to swing the carriage away from the grinding wheel as soon as the piston rod moves forward far enough to release the lever 47 to the force of the said spring.

15 We claim as our invention:

1. In a grinding machine the combination of a frame with a grinding wheel mounted thereon, a reciprocating carriage mounted on the said frame for moving back and forth 20 in front of the said grinding wheel, the said carriage having a cross arm, a hydraulic cylinder and piston with its piston rod connected with the said cross arm, a tripping lug mounted on the said piston rod, a latch 25 mounted on the said cylinder and adapted to be tripped by the said lug, a cock for controlling the flow of liquid into and out of the said cylinder, an operating handle for the said cock, a sliding bolt connected with the 30 said handle and adapted for being engaged by the said latch, and a spring acting upon the said sliding bolt for moving it and the said operating handle in one direction, whereby the said spring for moving the said operating handle in one direction is held under tension by the said sliding bolt and released 35 by means of the piston rod.

2. In a grinding machine, the combination of a reciprocating carriage having a cross 40 arm with a hydraulic cylinder, piston and piston rod, for operating the said carriage, the said piston rod extending transversely to the said cross arm, and adjustable collars mounted on the said piston rod for acting 45 upon either side of the said cross arm for operating the said carriage.

3. In a grinding machine, the combination of a frame with a swinging carriage bed pivoted thereon, a spring acting to swing the 50 said carriage bed in one direction, a reciprocating carriage mounted on the said swinging carriage bed and having a cross arm, a fixed bar on the frame extending longitudinally of the movement of the said carriage, a 55 hydraulic cylinder, piston and piston rod with the said rod extending transversely to the said cross arm, an angle lever mounted on the said carriage with one end extending transversely to the said piston rod and with 60 its other end in position for acting on the said bar, and adjustable collars mounted on

the said piston rod for acting upon either side of the said cross arm, and also, as to one of the said collars, for acting upon one arm of the said angle lever for swinging the carriage 65 bed in opposition to the said spring.

4. In a grinding machine, the combination of a frame with a swinging carriage bed pivoted thereon, a spring acting to swing the said carriage bed in one direction, a reciprocating carriage mounted on the said swinging carriage bed and having a cross arm, a fixed bar on the frame extending longitudinally of the movement of the said carriage, a hydraulic cylinder, piston and piston rod 75 with the said rod extending transversely to the said cross arm, an angle lever mounted on the said carriage with one end extending transversely to the said piston rod and with its other end in position for acting on the 80 said bar, adjustable collars mounted on the said piston rod for acting upon either side of the said cross arm and also as to one of the said collars for acting upon one arm of the said angle lever for swinging the carriage 85 bed in opposition to the said spring, and friction devices, one of which is fixed on the swinging bed and the other on the carriage for holding the carriage against its return movement until the said angle lever is shifted. 90

5. In a grinding machine, the combination of a hydraulic cylinder, piston and piston rod, with a cock for controlling the liquid passing into and out of the said cylinder, an operating handle for the said cock, a sliding bolt 95 connected therewith, a spring for moving the said bolt and handle in one direction, a latch for holding the said bolt with the said spring under tension, and a tripping lug on the piston rod for acting upon the said latch 100 to release the said bolt to the action of the said spring.

6. In a grinding machine, the combination of a reciprocating carriage having a cross arm with a hydraulic cylinder, piston and piston 105 rod, a cock for controlling the liquid passing into and out of the said cylinder, an operating handle for the said cock, a sliding bolt connected therewith, a spring for moving the said bolt and handle in one direction, a 110 latch for holding the said bolt with the said spring under tension, a tripping lug and adjustable collars on the said piston rod, the said lug acting upon the said latch to release the said bolt to the action of the said spring 115 and the said collars acting on the said cross arm to move the carriage forward and back.
